UNITED STATES PATENT OFFICE

2,370,275

FOOTWEAR

Eugene B. Ward, West Springfield, Mass.

Application February 1, 1943, Serial No. 474,285

4 Claims. (Cl. 36—76)

This invention relates to improvements in footwear and is directed more particularly to an improved shoe construction which is adapted to provide correct and sufficient support of the foot.

It is a principal object of the invention to provide a simple yet efficient supporting means for associating with a shoe of more or less conventional construction in such a way that the foot is properly supported both when it is relatively flat, as in standing, and when it is bent or flexed, as in walking. As will appear, according to the preferred form of the invention, this supporting means is built into the shoe as it is manufactured although it is to be understood that the same can be made separately and later placed in the shoe as an appliance.

As a special feature of the invention, the device or means includes a supporting member so arranged and adapted that it may support both the longitudinal arch and the metatarsal arch of the foot. As will be explained this member is capable of flexing movement relative to the rigid shank part or parts of the construction so that it assumes an arch-supporting position in all natural positions of the foot.

Broadly the device of the invention includes a relatively-stationary and rigid shank member and a spring-like member having a part rigidly connected to the shank member and so arranged that it is actuated into arch-supporting position when the sole of the shoe is flexed. It will be appreciated that the device may be associated with footwear for either men or women.

According to the preferred form of the invention, the device includes but two parts which are so connected together and so arranged that one part is moved relative to the other by the bending or flexing of the shoe as the wearer bends the foot. The construction in its broad aspects is adapted for use in connection with shoes of all types and sizes and it is simple in construction so as to be economical to manufacture.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawing wherein:

Fig. 1 is a side elevational view with dot-dash lines to indicate the preferred position of the device with reference to a man's shoe;

Fig. 2 is a top plan view of the preferred form of the device of the invention; and

Fig. 3 is a sectional view on the line 3—3 of Fig. 2.

Referring now to the drawing more in detail, the invention will be fully described.

A man's shoe is represented by dot-dash lines S and it has a heel h and outer sole s. There is a rigid shank member 10 which extends upwardly adjacent the longitudinal arch of the foot when the shoe is worn.

Member 10 is formed of substantially rigid metal so as to be relatively unbendable and it preferably has its rear end portion extending 15 into the heel part of the shoe, as indicated. The forward end of member 10 preferably terminates rearwardly of the so-called metatarsal arch region of the shoe, as shown.

The human foot has a row of what are referred 20 to as metatarsal heads which extend transversely thereacross and form the metatarsal arch. The means of this invention is calculated to support this region as well as the longitudinal arch of the foot.

Supporting member 20 is provided of relatively spring-like metal and it extends longitudinally of the shank member 10 and overlies 25 same as shown. The rear end portion of said member 20 is rigidly secured to the shank by some means such as a rivet 22, welding, or other suitable means.

Where the invention is built into a shoe, the member 20 overlies the shank which is commonly 30 found in shoes or if it takes the form of a separate appliance, the adjacently-disposed member 20 and shank 10 compose a unit which is placed in the shoe. In any event, it is usual to have a covering (not shown) of some flexible material such as leather to overlie the shank and supporting 35 members and this more or less serves as the inner sole of the shoe.

Member 20 may be variously formed but it preferably is substantially flat transversely 40 for the greater part of its length. Adjacent its forward end is a humped portion 24 and this is somewhat spoon-shaped as indicated in Figs. 2 and 3 for engaging the metatarsal arch of the foot.

Preferably, too, the forward end portion 26 of member 20 extends or projects beyond the forward end of the shank, as shown in Fig. 1, so as 45 to rest on the inside of the sole of the shoe.

It is to be understood, however, that the forward end portion of the supporting part 20 may 50 rest on or engage the upper side of the shank.

The important thing is that at least the humped part 24 of the spring-like member be normally spaced from the upper surface of the shank so as to be movable relative thereto when the foot is flexed.

The arrangement is such that when the sole of the shoe is bent the supporting member is moved relative to the stationary shank and thus supports both the metatarsal region and the longitudinal arch in all positions of the foot. The forward end portion of the spring support is preferably more or less enlarged as shown and while the bulge 24 is perhaps shown somewhat exaggerated, it nevertheless will be such as to engage the foot to a proper degree.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. As a new article of manufacture, a device of the class described comprising in combination, a rigid shank member, and a supporting member overlying said shank member and having its rear end portion fixedly secured to the shank member, the forward end portion of the supporting member being provided with an upraised part and being free of connection with the shank member, said supporting member projecting beyond the forward end of the shank member.

2. As a new article of manufacture, a device of the class described comprising in combination, a shank member having a rear end heel portion for positioning in the heel portion of a shoe and extending longitudinally forwardly therefrom for

positioning over the longitudinal arch of a shoe, and a support member having a rear end heel portion fixed to the heel portion of the shank member and extending forwardly therefrom over said shank, said support member being relatively more yieldable than said shank member, the forward end of the support member being free of connection with the shank member and extending beyond the forward end of said member with the forward end portion of the support member provided with an upraised part adapted to support the metatarsal arch of the foot.

3. As a new article of manufacture, a device of the class described comprising in combination, a shank member having a rear end heel portion and a body portion extending forwardly and downwardly therefrom, and a support member having a rear end heel portion fixed to the heel portion of said shank member and a longitudinal arch portion extending forwardly and downwardly therefrom over and diverging from the body portion of the shank member, the forward end of the support member extending beyond the forward end of the shank member and having an upraised metatarsal arch portion disposed inwardly of said forward end.

4. As a new article of manufacture, a device of the class described comprising in combination, a shank member having a rear end heel portion and a body portion extending forwardly and downwardly therefrom, and a support member having a rear end heel portion fixed to the heel portion of said shank member and a longitudinal arch portion extending forwardly and downwardly therefrom over and diverging from the body portion of the shank member, the forward end of the support member extending beyond the forward end of the shank member and having an upraised metatarsal arch portion disposed inwardly of said forward end, said support member being relatively more yieldable than said shank member.

EUGENE B. WARD.
